CLAIM

The ornamental design for a cargo mat, as shown and described.

DESCRIPTION

FIG. 1 is a front perspective view of a cargo mat, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof; and,

FIG. 11 is an enlarged detail view of area 11 in FIG. 2. The dash-dot-dash broken lines are provided for annotative purposes to graphically indicate the areas of enlargement. The dash-dot-dash broken lines do not represent actual structure and do not form part of the claimed design.

1 Claim, 11 Drawing Sheets
